GRAVITY FED, LIQUID-FUEL-PILOT-TYPE
OIL BURNER

Ralph W. De Lancey, Meriden, Conn., assignor,
by mesne assignments, to Miller Oil Burner
Company, Inc., Warren, Minn., a corporation
of Minnesota

Application October 4, 1950, Serial No. 188,334

15 Claims. (Cl. 158—91)

1 The present invention relates to gravity fed, liquid-fuel-pilot-type oil burners.

Gravity fed, liquid-fuel oil burners are usually operated either on an alternate high fire-pilot cycle or on a high fire-no fire cycle. In the latter, the burner is allowed to burn dry at the end of each high fire operation, while in the former, ignition is maintained between high fire periods by means of a gas or oil pilot. The oil pilot is more customarily employed.

The general practice, heretofore in use where oil pilot is employed, is to alternately feed fuel from a source at a substantially constant level at one metered rate for high fire and another for pilot, this fuel draining from the metering valve through suitable passages in the bowl of the burner and at high fire forming a pool in the burner bowl. When the fuel flow rate is reduced to the pilot rate, the fuel in the burner is gradually consumed so that the burner bowl burns dry except where the pilot fuel is admitted. This fuel continues to burn during the pilot period and provides ignition for the next high fire operation. As the pilot operates over long periods, economy requires the employment of as low a low pilot firing rate as can be successfully maintained.

There is a tendency for the accumulation of carbonaceous residues in the region where the pilot is maintained, especially when operating over long periods at pilot flame. The pilot fuel is usually received in a pilot well which fills to overflowing by the fuel flowing into the burner to maintain the pool for high fire. The pilot well residues are then submerged, and while wetting and softening of accumulated pilot fire residues facilitates the burning away of much of the same during the receding of the fuel to pilot feed, all such residues cannot be so disposed of, and accumulation of unburnable residues results in the region where the pilot flame has operated. The difficulties arising from accumulation of such residues have been greatly overcome by improved design of the burner, as, for example, in my Patent 2,423,808, July 7, 1943, but it has been impossible to so completely eliminate carbonaceous residues about the pilot as to equal the results where the cycle is of the high-fire-no-fire type.

The present invention contemplates improvements in the oil burners and controls for them and contemplates an improved means for operating liquid fuel pilot type gravity fed vaporizing burners.

In its broader aspects, the present invention

2 contemplates that the burner bowl, or vaporizer will have two inlets for fuel below the level to which the fuel is admitted to high fire, so that these inlets are then submerged. In the operation of the burner, with each alternate change in the rate of fuel supply to the selected rate, one or the other of the inlets is selected for the flow of fuel at the next pilot period. In some cases, the change is made when going from low fire to high, while in other cases when going from high fire to low fire. Accordingly, when the fire changes from high fire to pilot at the selected inlet, the fuel in the burner is burned away and the remainder of the fuel in and about the inlets is also consumed, but in view of the fact that no fuel is coming in through one of the inlets, this inlet is burned dry and any carbonaceous residue there consumed in a manner similar to that customary with similar burners having a single fuel line and operated on a high-fire-no-fire cycle, while at the other inlet pilot flame is maintained because fuel is fed to the burner at pilot rate through that inlet. In the next cycle of operations, the fuel supply is so controlled that pilot fuel is admitted through the inlet which previously had been burned dry and at least during pilot operation is cut off from the inlet where pilot operation took place in the preceding cycle. In this manner, at each alternate pilot fire period, one inlet burns dry while the other one maintains the pilot, and in each succeeding cycle the position where pilot operation took place shifts from where it was at the preceding pilot.

35 The method of operation above outlined may be obtained by manipulation of manually controlled valves, or automatically by suitable apparatus under remote control as, for example, by a room thermostat. Where the operation is to be manual, one can employ a constant level valve-metering valve unit having two manually operable metering valves shiftable between off, pilot, and high fire positions. Such valves are available for operating two separate oil burners and to carry out the above outlined process, the two outlet connections from such double metering valve unit are connected to the separate burner bowl inlets above referred to. While one such valve is closed, the other is opened for high fire, then reduced to pilot, the first remaining closed; then the first opened to high fire and when the pilot has ignited, the fuel fed through the second valve shifted from pilot to closed position, it remains closed through the next pilot period and reopened for the next high fire, etc.

Where the operation is to be carried out by remote control, as from a room thermostat, the room thermostat employed closes a circuit which operates a valve stem shifter to shift the valve stem from the pilot position to the high fire position so that the fuel drains from the metering valve at the high fire rate so long as the room thermostat calls for heat, and upon satisfaction of the demand for heat, the flow rate is automatically shifted to the pilot rate. The preferred form of valve operator includes a heater coil in the thermostat circuit and a bimetallic valve stem operator. The single metering valve stem may of course be shifted back and forth manually instead of by remote control, if desired.

The fuel draining from the metering valve passes into a single conduit and between this single conduit and the burner bowl inlets, provisions are made for controlling the flow so that at least during alternate pilot operations fuel can flow only through one line to the burner bowl and the inlets are alternately used in the successive pilot fire operations. The controls employed may, according to the present invention, take various forms where the flow rate control is effected electrically as from the room thermostat.

Where the bimetal operated type of metering valve with remote controlled heater is employed, the movable bimetal element may be used to control an auxiliary circuit in series with the room thermostat and in shunt with the heater circuit for effecting the shift of a selector valve member which selects the path through which the fuel is to flow to the burner bowl. Such a circuit may be energized at every other operation of the metering valve or each operation of the metering valve. In constructions in which an upper passage to one of the burner inlets is at all times open and the other passage at a lower level is alternately made available by the selector valve during pilot fire operation, a circuit energized every other high fire period may be employed. The selector valve may be biased to open said lower passage or to close it. Where it is biased to open said passage, failure of the operating circuit will allow the fuel to flow through the lower passage at each pilot period. Should the valve member be removed (in either case), the fuel will flow through the lower passage at each pilot period. Under these conditions, the burner operates on one pilot until it clogs, whereupon the oil supply is continued through the higher passage and pilot operation continues there until repeated cycles of operation effect a consumption of residues at the first pilot and it resumes operation.

In constructions where the auxiliary circuit is actuated each cycle of metering valve operation, the closing of the auxiliary circuit is utilized to actuate a selector valve member which closes the fuel passage to the inlet at which pilot flame has been burning and opens the passage to the other inlet and keeps it open throughout the remainder of the high fire period and succeeding pilot period.

The electrical control devices employing the heater operated bimetal metering valve opener may conveniently inherently have a delay opening or closing of the auxiliary circuit as the case may be on account of the time delay factor in the heated bimetal.

Where, however, the metering valve is manually controlled for high fire and for pilot operation, or where conventional thermally operated

metering valves are employed without provision for controlling auxiliary circuits, one can effect the auxiliary control of the fuel after it leaves the metering valve by hydraulic devices actuated by the fuel. When the fuel is supplied to the burner at the high fire rate, it raises in the burner bowl and connecting passages to the maximum amount as determined by the fuel level in the constant level valve, and when the firing rate is reduced to the pilot rate, the fuel level in all the passages beyond the metering valve recedes to a level which is sufficient to cause the fuel to flow into the pilot. This difference in level may according to certain forms of the present invention be employed to operate liquid level responsive devices, and these liquid level responsive devices be employed to effect the shift of a suitable selector valve member to control the fuel flow to one inlet and then to the other in the desired sequence. Inasmuch as both fuel inlets are submerged during high fire, a single liquid level responsive device may be employed. At each high fire operation such a liquid level responsive device would be at its maximum elevation and would lower to its lowest position during pilot operation irrespective of whether liquid were flowing through the passage for pilot or not.

The accompanying drawings show, for purposes of illustrating the present invention, several embodiments in which the invention may take form, it being understood that the drawings are illustrative of the invention rather than limiting the same.

In the accompanying drawings:

Figure 1 is a top plan view illustrating a burner bowl with two inlets, a constant level and metering valve unit, together with one type of control for selecting the burner inlet employed;

Figure 17 illustrates a selector valve suitable for hydraulic operation and arranged to divert all the fuel to one or to the other of the pilot wells; and

Figure 18 is a diagrammatic view illustrating a form of construction employing manual controls for obtaining pilot operations alternately at the well.

The bowl of a vaporizing pot type oil burner is shown at 20 (Figs. 1 and 2). This bowl carries a central air distributor 21 and spreader 22, and is received in a housing 23. Above the vaporizer 20 is a perforated tube 24 and the top of the housing carries a ring 25. These parts, together with the baffles indicated at 26 and 26' may be constructed in accordance with my Patents 2,290,544, 2,423,808, and 2,373,814. A forced draft is provided through a draft tube indicated at 27 and oil is received in the burner bowl through two pilot wells A and B. These pilot wells are close to one another but are separated by a partition or dividing wall 30 at the same level as the burner bowl surface indicated at 31.

The fuel is supplied to the burner from a fuel supply line 40 which is connected to a combined constant level and metering valve generally indicated at 41. Any convenient form of constant level-metering valve construction may be used. Such combination valves have one or two outlets such as the one shown at 42. Various forms of metering valves are used in such constructions. In some cases the metering valves are biased toward closed position and in other cases toward an open position. For convenience, the movable metering valve member 43 is of the type which is biased toward closed position and shifted toward open position by a bimetal thermostat element indicated at 44 as set forth more in detail in my Patent No. 2,359,024. Such metering valve stem has a small hole 45, slightly below the upper surface of the oil as indicated in Figure 7, to supply fuel for pilot.

The bimetal operator 44 for the metering valve 43 is energized by heat from the resistor 46 connected to the usual control circuit which includes transformer T, room thermostat 47 and limit switch 48. The constant level valve mechanism in valve 41 keeps the oil level at substantially the constant level indicated, and when the bimetal operator 44 for the metering valve is cold, fuel flows through hole 45 to maintain pilot at all times. When the control circuit is closed, the bimetal warps and opens the metering valve to the high fire position in the usual manner, so as to supply fuel at a high rate for high fire.

In the construction shown in Figure 7, the end of the bimetal member 44 carries a pawl 49 co-operable with a ratchet wheel 50 carried on a shaft 51, so that each time the heater 46 operates the bimetal element 44, the ratchet and pawl mechanism advances the shaft 51 one tooth. The shaft 51 operates a cam wheel 52 having deep notches indicated at 53 alternating with shallow notches indicated at 54. These notches are equally spaced and of the same number as the teeth on the wheel 50. They form a cam surface on which bears a contact carrying spring 55. This spring is opposite a fixed contact 56 connected

to the transformer by wiring indicated at 57. The movable contact 55 is connected by wire 58 with heater coil 59 so as to provide a circuit in parallel with the heater circuit 46 and adapted to be opened or closed, depending upon whether the movable contact 55 is in the deep or shallow notch of the cam 52.

As shown in Figures 4 and 7, the switch elements 55, 56 are in the open circuit position and the heater 59 is deenergized. The heater 59 is close to a bimetal warp element 60 whose free end carries a vertical movable plunger 61. When the coil 59 is cold, the plunger is held up as shown in Figure 4, and when the coil 59 is heated, the warp bar 60 forces the plunger 61 down as indicated in Figure 5. The plunger 61 is carried in a valve housing 62 and enters into a chamber 63 in this housing.

This chamber 63 has a bottom connection 64 coupled to a tube 65 whose other end is secured to the outlet connection 42 from the metering valve. The chamber 63 includes a lateral drilling 66 from the left and a lateral drilling 67 from the right. The drilling 66 is slightly lower than the drilling 67 so that the bottom of the drilling 67, where it intersects the drilling 66 and inlet opening 64' forms an obstruction 70, at an elevation above the bottom of the left drilling 66. The left drilling 66 is intersected by a horizontal outlet passage 71, while the right-hand drilling 67 is intersected by a horizontal outlet passage 72. The passage 71 is at a lower level than passage 72. The passages 71 and 72 lead toward the burner and are connected to the pilot wells A and B by tubes 73 and 74. The tubes 71 and 72 are provided with vents as indicated at 75 and 76, so that fuel can rise and fall in accordance with the hydraulic head existing.

A mounting bracket 80 is secured to a plate 81 adapted to be placed over the door opening of the furnace. The bracket 80 has an arm 82 which supports constant level-metering valve assembly 41, a second arm 83 which supports controls generally indicated at 84 and also is formed into a box-like chamber or air chest 85 into which the vent tubes 75 and 76 enter. This chamber is open at the left as indicated in Figure 2 and a motor operated blower unit 86 is secured to the housing so as to provide a blast of air into the housing 85. The air duct 27 interconnects the pressure chamber 85 and the burner so that air may be blown from the chamber 85 through the duct to supply the burner with air for combustion. The tubes 73 and 74 pass through this duct as indicated in Figures 1 and 2. The selector valve 62 is secured to the front well of the chamber 85 by a bolt as indicated at 87.

In the operation of burners such as described, the blower 86 is intended to operate continuously so as to provide continuous draft to the burner. The burner itself is adapted to burn liquid fuels of the catalytic cracked type having high carbonaceous residues, but difficult to burn in pot burners as discussed in my patents above referred to, and it is contemplated that such a fuel will be supplied to the present equipment.

If it is assumed that the parts are in the position shown in Figures 4 and 7 of the drawings, and the burner is operating at pilot, there will be a pilot flame in the pilot well A, which is favored because of the fact that it is connected to the lower side of the selector valve chamber which is open to the fuel supply. The fuel level is as shown in Figure 4. At this time the valve

61 is up so that at pilot operation, all the fuel flowing through the closed metering valve will go to pilot A. At this time, as shown in Figure 7, the pawl 49 is down and the switch element 55 is resting in a high notch 54 so that the switch 55, 56 is open and the bimetal element 60 cold.

If there is a demand for heat, the metering valve heater 46 will cause the bimetal 44 to bend upwardly and gradually open the metering valve to increase the flow rate to the high rate. This opening takes a measured length of time so that the flow is not immediate and sudden. During the lifting of the bimetal 44, the pawl 49 will be lifted up and the index wheel 50 shifted one tooth. This shift will cause the end of contact 55 to enter into a deep notch 53 and close the circuit at 55, 56, thereby energizing the heater 59. This is a relatively slow acting heater and it will heat the bimetal 60 causing it to bend down and lower the plunger 61. During the time consumed for these operations, the oil at higher rate of feed will fill the pilot well A to a level high enough to cause it to flow over the obstruction 70 and down through pipe 72, 74 to pilot well B. The timing is such that oil will have risen out of the pilot wells so that combustion will take place in or near both pilot wells, so that the shifting of plunger valve 61 down to the position of Figure 5 does not cut off or affect the high fire operation. This high fire operation will continue as long as the heat is demanded, and for this entire period both heaters 46 and 59 will hold the valve stem 43 up and the valve stem 61 down.

When the heating required is satisfied, and the heater 46 deenergized, the metering valve goes to closed or pilot position and the pawl 49 drops down below a tooth. This does not affect the circuit through heater 59 so that the plunger 61 will continue to be held down. Fuel in the burner bowl will be consumed and all the fuel in pilot well A and the line leading to it will be burned away. Fuel, however, will run down through line 72, 74 so that pilot is maintained in pilot well B. Air from air chest 25 will enter tubes 75 and 76 and pass through the pilot wells to provide air for combustion.

The next time there is a demand for heat, the metering valve is slowly opened and fuel flows through the fuel lines to pilot well B. This operation of the metering valve will shift the index wheel 50 one more tooth and will shift the cam 52 to a position to open the circuit for heater coil 59 so that the bimetal 60 will cool and plunger 61 will rise. Its movement is ineffective at this time for the burner is operating at near high fire and fuel can flow down through both lines.

At the end of this second high fire operation, however, the fuel in the burner bowl will be consumed as well as that in pilot well B and the line leading to it. Pilot operation, however, will be maintained in pilot well A.

This cycle of operation continues indefinitely and after each pilot operation in one well, there is a pilot operation in the other well and the carbonaceous residue which was left from the previous pilot operation will be consumed when that well is burned dry. The burner, therefore, operates so far as burning away carbonaceous residues out of the pilot well is concerned, in the same manner as a similar dry well burner ignited electrically or by torch.

With the arrangement shown in Figures 4 to 7, the disabling of the selector valve circuit or

removal of plunger 61 reduces the operation of the burner to a condition where there is continuous operation in the favored pilot well, namely, pilot well A, for in such cases, during pilot operation, as long as pilot A can operate, it will receive all the pilot fuel. Under such circumstances, should burner operation continue until that pilot well is clogged or seriously impaired by reason of accumulated carbonaceous residues, the fuel will accumulate in the chamber of the selector valve and arise to a sufficiently high level to overflow the dam and pass into well B, start ignition there and automatically transfer pilot operation to well B. Operation will continue from well B until the residues have been burned away from well A sufficiently to permit it to dominate and take all the pilot fuel.

In the arrangement shown in Figure 7a, all the parts are generally like those shown in Figures 4 to 7, except that the cam wheel 52 is advanced or retarded one tooth, and the bimetal element 60 is reversed so as to be bent up when heated instead of down. Then the selector valve is normally in closed position of Figure 5 when the heater 59 is cold and is shifted to the open position of Figure 4 when the heater 59 is energized. The arrangement shown in Figure 7a does not, however, function the same as shown in Figure 7 in case the selector valve is disabled for then the valve stem 61 is biased down and the fuel would always flow down through pilot line 72, 74 to pilot well B which would operate each pilot period.

In the construction shown in Figures 8 to 14, inclusive, the same structures are used, except for the selector valve and its controls and corresponding reference characters are applied to these figures without specific enumeration of the same. Here the control circuit having a transformer T, room thermostat 47 and limit switch 48, is connected by wiring 101 and 102 with a heater coil 103 below a bimetal member 104. The bimetal element 104 is connected by a wire 105 with a small synchronous motor 106 and this motor is connected by wire 107 with the transformer lead 101. The bimetal element 104, when in the pilot position, engages a contact 108 connected by wire 109 with the wire 102 so that the circuit to the synchronous motor is completed, except for the opening at the room thermostat 47 or at the limit switch 48. When the circuit through these is closed, the motor 106 is energized. This motor through reduction gearing in the housing 110 drives a shaft 111 at a slow speed, for example $\frac{1}{5}$ R. P. M. The motor 106 and gearing housing 110 are mounted on top of a selector valve casing 112. This casing has a vertical bore 113 which receives a vertical valve stem 114. This valve stem is freely rotatable in the bore and has a non-circular opening 115 into which the flattened portion of the shaft 111 enters as shown in Figure 13. The valve member 114 is provided with an enlarged head 116 having two cutouts or notches indicated at 116a and 116b. The motor turns the member 111 in a clockwise direction as indicated in Figure 14. An insulating plunger 117 carried in an insulated support 118 is urged against the valve head 116 by a spring 119 carrying a contact 120 cooperating with contact 121 connected to the transformer by the wire 122. The spring contact 119 is connected by wire 123 with the wire 105.

The circuit through the contacts 120-121 is open at the end of a cycle as shown in Figure

14, but when the thermostat calls for heat, the motor starts into operation and during the time it takes the bimetal element 104 to open the circuit at 108, the motor 106 has turned the stem 114 far enough to pass the cutout 116b beyond the plunger 117. This will close the circuit at 120—121 and provide a running circuit for the motor 106 until the valve member 114 is turned one-half a revolution when the plunger 117 drops into the cutout 116a. This will stop the motor, the starting circuit having previously been opened by the bimetal 104.

The valve member 114 is open at the bottom as indicated at 122 so as to receive fuel delivered to the valve casing 112 through piping 123. The lower end of the valve stem has a cutout portion as indicated at 125 adapted to deliver oil to the left or to the right, depending upon the position of the valve stem. In the drawings, it is shown as delivering oil to the left where it can flow through a passage 126 in the casing to a filter receiving chamber 127. This filter chamber communicates with the oil line 73 leading to pilot A. Diametrically opposite to the passage 126 is a similar passage 128 leading to a filter chamber 129, which, in turn, communicates with the pipe 74 leading to pilot B. The filter chambers are closed by plugs 130 and bridging strap 131. The oil lines are provided with vents 132, 132 the same as those above described, and these enter the air chest 85 as previously set forth.

In the arrangement shown in Figures 8 to 14, the cycle of operations is similar to that above described. Here pilot fuel flows to pilot well A when the parts are in the position shown and when a high fire operation is to be commenced, the synchronous motor 106 is first set into operation to close its running circuit and shortly thereafter the bimetal 104 opens the metering valve 43 to allow oil to flow at high rate for high fire. This high flow rate oil is delivered to pilot A. After the valve 114 is turned somewhat more than a quarter of a revolution, it will deliver oil to both lines and to both pilot wells so that for a time oil is flowing into the burner through both pilot wells. When the valve 114 has been turned through the full 180°, oil flow will have been cut off to the line leading to pilot A and all the oil will be delivered to pilot B. The synchronous motor 106 will then have stopped and the high fire operation will continue until the control circuit is opened. The bimetal 104 will then cool and allow the metering valve to close so that pilot fuel will then flow down through pilot B. Operation will continue at pilot B until the bimetal 104 is again heated to start a new high fire cycle, whereupon the operation will continue at pilot B, and shift to pilot A in the manner above described.

In Figures 15 and 16 a form of construction operating in a hydraulic manner is diagrammatically shown. It employs an arrangement having two oil levels with dam and shift valve of the type shown in Figures 1-7, but has no electrical operating parts. Here the oil inlet 159 is assumed to be connected to a constant level-metering valve arranged to provide fuel at high rate for high fire and pilot rate for pilot fire. Such a valve mechanism may, for example, be manually controlled or of the remote controlled thermostatic type, or the solenoid type.

Figure 15 shows the parts in position for delivering pilot fuel through oil line 151 to pilot

B. The selector valve member 152 is down, as is corresponding member 61 (Fig. 5). Oil comes in through supply line 150, overflows the obstruction 153, and as shown by the full line arrows supplies pilot B. In its passage to B it flows over the floor 154 of a float chamber 155. This chamber accommodates a float 156 which is in lowered position.

When the flow rate is increased oil flows through the chamber passage 151, pilot well B, and rises in the burner bowl to the high fire operating level. This causes the float 156 to rise. The float is connected to a bell crank 157 rotatably carried in a shaft 158. The bellcrank carries a pawl 159 cooperable with a ratchet wheel 160 keyed to the shaft so that the shaft is turned a corresponding amount, here $\frac{1}{3}$ of a revolution.

The shaft 158 carries a cam 161 which in the form shown has four high spots 161a and four low spots 161b. In the position shown a high spot 161a bears on the upper end of the valve member 152 and forces it down against a lifting spring 162. Turning the shaft 158 one tooth turns the cam so that a low spot 161b is opposite the valve member 152 and the spring lifts it. This permits oil to enter passage 163 at lower level than the top of obstruction 153 and pass to the burner through pipe 164 and pilot well A. Before this valve 152 will have been fully opened, oil may have flowed from B to the burner bowl and back up pipeline 164, but this is of no importance in the cycle.

On reduction of the flow rate to the pilot rate, the oil will be consumed in the burner bowl, the pilot well B burned dry and the float allowed to drop. Oil will have continued to flow to the favored well A and pilot operation will continue there.

The next time fuel flow is increased to high fire it flows into pilot A and overflows the obstruction 153 and flows past the float to pilot well B. This will cause the float to rise and shift the cam so that the next high spot will engage valve member 152 and close the selector valve. High fire continues and in the next pilot operation well A is burned dry and well B is the pilot well.

The sequence of shifter valve, float and pilot operations is illustrated in Figure 16.

In the arrangement shown in Figure 17, the selector valve resembles that of Figures 8 to 14. The fuel is delivered from the metering valve to a chamber 170 in a valve body 171. This body has two outlets 172 and 173 adapted to be connected as before to pilot wells A and B. The chamber 170 receives a vertically reciprocable valve member 174 with outlets 175 and 176 at two levels. The valve member is biased upwardly by a spring 177 against a cam 178 similar to cam 161 and operated by a similar float and ratchet and pawl mechanism.

When the valve member 174 of Figure 17 is pressed down, as shown, fuel flows through the outlet 173 only and when released the fuel flows through outlet 172 only. There is also a period during which fuel flows through both outlets. In this arrangement the float is in one fuel line (for example the one leading to pilot B), but it rises in response to fuel flowing at high fire rate into pilot A because of the overflow into B and reverse flow up through pipe 173. It lowers whenever the burner consumes the fuel to reduce its level.

Figure 18 illustrates diagrammatically another

form of construction in which alternate pilot operation can be carried out. Here constant level-metering valve 180 is of the conventional type having two metering valves 181, 182, capable of individual control to high fire, pilot, or off positions. Such valves may be manually or thermally operated and are in use for controlling from one constant level valve fuel flow to one or the other or both burners of cook stoves, ovens and the like. Here one metering valve such as 181 is connected to pilot well A, while metering valve 182 is connected to pilot well B. As each has a fully open position, a pilot position, and an off position, one can shift pilot operation from one pilot well to the other at will.

Since it is obvious that the invention may be embodied in other forms and constructions within the scope of the claims, I wish it to be understood that the particular forms shown are but several of these forms, and various modifications and changes being possible, I do not otherwise limit myself in any way with respect thereto.

What is claimed is:

1. A vaporizing, gravity fed, pot type, liquid fuel burner comprising a vaporizer having two separated pilot wells depressed at the bottom of the pot, each provided with an inlet, a source of substantial-carbonaceous-residue liquid fuel at a substantially constant level higher than the pilot wells and sufficient to produce in the vaporizer a pool of fuel at substantially said higher level, means to regulate flow from said source at either a low rate for pilot operation or at a high rate for high fire operation, means operable when the flow rate is at the low rate to direct fuel from the said flow regulating means to the inlet of a selected one of the pilot wells, whereby upon continued pilot operation carbonaceous residues are accumulated therein, and upon subsequent increase of rate to continue flow to the same well, means, effective after a lapse of time after the initiation of flow at the high firing rate sufficient to fill the first well, cover residues therein with liquid fuel and cause fuel to overflow into the second well, for redirecting the flow of fuel to the inlet of the second well and for cutting off flow of fuel to the first well, whereby, upon reduction of flow into the second well to the pilot rate, the fuel in the burner and the first well, together with carbonaceous residues therein, are consumed and ignition is maintained by fuel in the second pilot well.

2. A vaporizing, gravity fed, pot type, liquid fuel burner comprising a vaporizer having two separated pilot wells depressed at the bottom of the pot, each provided with an inlet, a source of substantial-carbonaceous-residue liquid fuel at a substantially-constant level higher than the pilot wells and sufficient to produce in the vaporizer a pool of fuel at substantially said higher level, remote controlled, electrically operated means to regulate flow from said source at either a low rate for pilot operation or at a high rate for high fire operation, means operable when the flow rate is at the low rate to direct fuel from the said flow regulating means to the inlet of a selected one of the pilot wells, whereby upon continued pilot operation carbonaceous residues are accumulated therein, and upon subsequent increase of rate to continue flow to the same well, electrically timed means, effective after a lapse of time after the initiation of flow at the high firing rate sufficient to fill the first well, cover residues therein with liquid fuel and cause fuel to overflow into the second well, for redirecting the flow of fuel to the inlet of the second well and cut off flow of fuel to the first well, whereby, upon reduction of flow into the second well to the pilot rate, the fuel in the burner and the first well, together with carbonaceous residues therein, are consumed and

the flow of fuel to the inlet of the second well and for cutting off flow of fuel to the first well, whereby, upon reduction of flow into the second well to the pilot rate, the fuel in the burner and the first well, together with carbonaceous residues therein, are consumed and ignition is maintained by fuel in the second pilot well.

3. A vaporizing, gravity fed, pot type, liquid fuel burner as claimed in claim 2, wherein the electrically operated flow regulating means includes a heater controlled, bimetallic valve actuator and the timing means includes a delayed action device in parallel with the heater.

4. A vaporizing, gravity fed, pot type, liquid fuel burner as claimed in claim 2, wherein the electrically operated flow regulating means includes a heater controlled, bimetallic valve actuator and the timing means includes a motor in parallel with the heater, the motor having a starting circuit opened by the bimetallic operator and a self established running circuit automatically opened after a predetermined number of revolutions of the motor, and a motor driven valve stopped in either of two positions in one of which it admits fuel to but one well inlet and the other of which it admits fuel to the other well inlet only.

5. A vaporizing, gravity fed, pot type, liquid fuel burner as claimed in claim 2, wherein the electrically operated flow regulating means includes a heater controlled, bimetallic valve actuator and the timing means includes, a second heater, a cycling switch operated by the bimetallic valve operator for connecting the second heater in parallel with the first on alternate actuation of the bimetallic valve operator, a second valve operated by the second heater and disposed in the passages leading to the said selected pilot well, to open and close the same, the passage to the other pilot well being at all times open but including an obstruction to fuel flow at an elevation which diverts fuel at the low firing rate through the last mentioned valve when the latter is open.

6. A vaporizing, gravity fed, pot type liquid fuel burner comprising a vaporizer having two separated pilot wells depressed in the bottom of the pot and each provided with an inlet, a source of substantial-carbonaceous-residue liquid fuel at a level higher than the pilot wells and sufficient to produce in the vaporizer a pool of fuel at substantially said higher level, means to regulate flow from said source at either a low rate for pilot operation or at a high rate for high fire operation and having a single outlet, a two position flow selector valve having an inlet receiving fuel from the outlet of the flow regulating means and two outlets, one connecting with each well so that fuel may be directed to a selected well and during continued pilot operation thereat residues are accumulated, which are covered over by fuel upon subsequent increase of flow rate to that well, operating means for the flow selector valve, effective after a lapse of time after the initiation of the high firing rate sufficient to fill the first well, cover the residues therein with liquid fuel and cause fuel to overflow into the second well, for changing the valve position to redirect the flow of fuel to the inlet of the second well and cut off flow of fuel to the first well, whereby, upon reduction of flow into the second well to the pilot rate, the fuel in the burner and the first well, together with carbonaceous residues therein, are consumed and

ignition is maintained by fuel on the second pilot well.

7. A vaporizing, gravity fed, pot type liquid fuel burner as claimed in claim 6, wherein the flow selector valve includes a vertically reciprocating valve stem.

8. A vaporizing, gravity fed, pot type liquid fuel burner as claimed in claim 6, wherein the flow selector valve includes a vertically reciprocating valve stem in the passages leading to one well and having in the passage to the other well an obstruction to liquid flow which diverts fuel through the selector valve when open.

9. A vaporizing, gravity fed, pot type liquid fuel burner as claimed in claim 6, wherein the flow selector valve includes a rotary valve which interrupts flow to one well or to the other.

10. A vaporizing, gravity fed, pot type liquid fuel burner as claimed in claim 6, wherein the regulating means includes a bimetallic thermostat and an electric heater for the thermostat, and the flow selector valve operating means includes a switch in parallel with the electric heater.

11. A gravity fed liquid fuel burner having alternate high fire operation and low fire or pilot operation, comprising a source of liquid fuel at a substantially constant level, flow rate control means for controlling the rate of flow of fuel from the source at either a low rate for pilot or at a high rate for high fire, a vaporizing, pot type burner bowl adapted to contain at high fire a consumable pool of liquid fuel and having two fuel inlets below the level of the source, means operative without effecting cessation of flow to the bowl for intercepting flow of fuel to one burner bowl inlet while diverting it to the other bowl inlet so that upon burning away the pool of fuel in the bowl consequent upon lowering of flow rate to the pilot rate, pilot combustion is maintained at said other inlet, while at the first inlet the burner bowl is burned dry, and means to recycle the intercepting and diverting means once for each high fire operation of the control means to alternately supply the inlets with pilot fuel.

12. Oil burning apparatus comprising a source of liquid fuel at substantially a constant level, a metering valve controlling the rate of flow from the source, biased toward a low fire position and movable to a high fire position, an electrically energizable metering valve operator having a remote control circuit, a fuel drain from the metering valve having a receiving portion and a discharging portion, the latter having two branches, a second circuit including a switch sequentially controlled by the metering valve operator and in parallel with the first circuit, said second circuit including an electrically energized second valve operator, a second valve means receiving all fuel from the receiving portion of the fuel drain and transmitting it to one only or both of the discharge portions and including a movable member operated by the second valve operator on alternate energizations of the metering valve operator to close off a selected branch so that the fuel must drain through the other branch, and a burner having a vaporizing pot receiving the discharge from both passages.

13. A vaporizing, gravity fed, pot type, liquid fuel burner comprising a vaporizer with two separated pilot wells depressed in the bottom of the pot, a source of liquid fuel at a substantially constant higher level to produce in the vaporizer a pool of fuel at substantially said higher level, a

metering valve for regulating fuel flow from said source at either a low rate for pilot operation or at a high rate for high fire operation, means forming a biforked passage connecting the metering valve and the pilot wells, flow control means effective at the pilot flow rate to direct the fuel through one only of the passages to one of the pilot wells and for directing the fuel to the same well on increase of the firing rate, so that it overflows in the vaporizer into the other pilot well, and for thereafter directing the fuel at the high firing rate through the other passage and interrupting flow through the first passage so that upon subsequent reduction of flow rate the fuel remaining in the first well is completely consumed while pilot operation is continued in the second well, said flow control means including a movable valve member, and means effective after a lapse of time after initiation of flow at the high rate for actuating the movable valve member to redirect the fuel flow.

14. In a liquid fuel heating system, in combination a liquid fuel supply means including a fuel flow rate control valve having a high rate for heating and a low or pilot rate and alternately shiftable back and forth therebetween, a vaporizing, pot type burner bowl having two fuel inlets and adapted when supplied with fuel at the high firing rate to burn it from a pool, and means cyclically controlled with the shifting of the flow rate control valve for directing the fuel when flowing at the low or pilot rate to first one bowl inlet and then after each intervening high fire rate of flow to the other so that the one not supplied burns dry, while at the one supplied a pilot is maintained.

15. A vaporizing, gravity fed, pot type, liquid fed burner comprising a vaporizer with dual pilot wells depressed in the bottom of the pot, a source of liquid fuel at a substantially constant higher level to produce in the vaporizer a pool of fuel at substantially said higher level, a metering valve movable between positions, in one of which the fuel flows at a low rate for pilot operations and in the other of which the fuel flows at a high rate for high fire operations, the metering valve having a single outlet, a fuel diversion valve accepting fuel from the metering valve outlet and having two outlets each connected to one of the pilot wells and a movable member operable between two positions in one of which it obstructs flow to one of the pilot wells at both rates of flow without interfering with flow to the other, the diversion valve also having passages to allow flow to said other well.
